UNITED STATES PATENT OFFICE.

BRIDGET ELLEN BURKE, OF MALONE, NEW YORK.

DESIGN FOR AN EMBLEM.

• No. 39,633.

Specification for Design.

Patented Oct. 27, 1908.

Application filed August 27, 1908. Serial No. 450,591. Term of patent 7 years.

To all whom it may concern:

Be it known that I, BRIDGET ELLEN BURKE, a citizen of the United States, residing at Malone, county of Franklin, and State of New York, have invented a new, original, and ornamental Design for Emblems, of which the following is a specification, reference being had to the accompanying drawing, forming part thereof.

In the drawings, the emblem of my invention is shown in perspective.

I claim:

The ornamental design for an emblem, substantially as shown.

BRIDGET ELLEN BURKE.
